(57) **CLAIM**

The ornamental design for an electric power socket track, as shown and described.

DESCRIPTION

FIG. 1 is a front view of an electric power socket track showing our new design;

FIG. 2 is a rear view thereof;

FIG. 3 is a left side view thereof;

FIG. 4 is a right side view thereof;

FIG. 5 is a top plan view thereof;

FIG. 6 is a bottom plan view thereof;

FIG. 7 is a front perspective view thereof;

FIG. 8 is a rear perspective view thereof;

FIG. 9 is a cross-sectional view thereof as seen from line 9-9 in FIG. 1;

FIG. 10 is an enlarged detail view of portion 10 shown in FIG. 1;

FIG. 11 is an enlarged detail view of portion 11 shown in FIG. 1;

FIG. 12 is an enlarged detail view of portion 12 shown in FIG. 2;

FIG. 13 is an enlarged detail view of portion 13 shown in FIG. 2;

FIG. 14 is an enlarged detail view of portion 14 shown in FIG. 2;

FIG. 15 is an enlarged view of FIG. 5; and,

FIG. 16 is an enlarged view of FIG. 6.

Broken lines depict portions of electric power socket track that form no part of the claimed design.

1 Claim, 14 Drawing Sheets
